UNITED STATES PATENT OFFICE.

LAWRENCE GLENN, OF OTTUMWA, IOWA, ASSIGNOR OF TWO-THIRDS TO
BENJAMIN COLE AND W. H. C. JAQUES, OF SAME PLACE.

AIR-BRAKE.

SPECIFICATION forming part of Letters Patent No. 234,179, dated November 9, 1880.

Application filed October 8, 1878.

To all whom it may concern:

Be it known that I, LAWRENCE GLENN, of Ottumwa, in the county of Wapello and State of Iowa, have invented a new and Improved 5 Air-Brake, of which the following a specification.

My invention relates to the lever that is operated upon by the piston-rod of the air-cylinder; and its object is to simplify the construction of the parts generally employed, and to obtain greater power.

The invention will be understood as set forth in the following specification and claim.

In the accompanying drawings, Figure 1 is a side elevation of my improved device attached beneath a car, in connection with an air-cylinder. Fig. 2 is a plan view of said devices.

Similar letters of reference indicate corresponding parts.

a represents the bottom of a car, to which is attached a hanger, *b*, in a convenient position for the operation of the brake mechanism. The hanger *b* is formed with a box, *c*, through 25 which passes a lever, *d*, which is held by a fulcrum pin or bolt, *e*. The pin *e* passes through the lever *d* at the center of the length of the lever, so that the lever *d* projects an equal distance each side of hanger *b* in a direction 30 transversely of the car.

f is the air-cylinder, of usual construction, having a piston-rod, *g*, and a piston (not shown) that is operated by means of a vacuum or compressed air, in any well-known manner, through the medium of pipes. (Not shown.) The forked end *i* of the piston-rod *g* is connected to the lever *d* by a pin, *k*, that passes through a slot, *x*, in the lever *d*, and may or may not carry a friction-roller, so that the 35 lever and piston will move together and the piston retain its position parallel with the length of the cylinder.

It is evident that to secure even action and durability of a brake, and especially of the air-cylinder, it is important and necessary that the action of all the parts be easy and normal. I secure this action in the piston of the air-cylinder by providing a means of keeping said piston exactly straight with the line of the 45 cylinder, effected by providing the lever to which the piston-rod is attached with a slot, *x*, as above described. This insures an action 50

of an exact even character, and is a simple device for attaining an end which is very essential to air-brakes, and which has not hitherto been reached.

l is a rod or arm having a forked head, *m*, that is connected to lever *d* at the side of fulcrum *e* opposite to the piston-rod *g*. The arm *l* is attached by a pin, *n*, which permits it to 60 swing freely, and its free end passes loosely through a hole in the stud *o* that is rigidly attached to the car bottom *a*.

h is a spiral spring around the arm *l* and bearing against the stud *o* and head *m*. 65

At each end of lever *d* is a hole, *r*, for the connection of the rods or chains of the brakes, and the connections to the brake-shoes may be made direct, if desired.

The brakes are applied by the action of the 70 air in the cylinder *f* forcing out the piston-rod *g* and piston, thereby operating the lever *d*. This action compresses spring *h*, so that when the pressure is taken off the spring *h* it will quickly relieve the brakes and return the lever 75 *d* to its normal position.

The mechanism described dispenses with the trusses, guides, and other complicated parts generally used with air-brakes. The piston has great leverage in operating the 80 brakes, and there is very little friction to be overcome.

I am aware that brakes constructed on the principle of mine have been used, but they lack the simplicity and efficacy of mine. I 85 therefore do not claim, broadly, a pivoted lever and compensating-spring; but what I do claim is—

The herein-described air-brake, consisting of the lever *d*, pivoted in the center in the 90 hanger *b*, and provided near one end with the slot *x*, the rod *l*, with forked end *m*, pivoted near one end of said lever, the spring *h*, surrounding the rod *l*, guide *o*, through which said rod passes, the air-cylinder *f*, piston and 95 piston-rod *g*, and forked head *i*, pivoted near the other end of the lever in the slot *x*, all constructed and arranged to operate substantially as set forth.

LAWRENCE GLENN.
